UNITED STATES PATENT OFFICE.

JOHN L. VAN NESS, OF BROOKLYN, NEW YORK, ASSIGNOR TO WICHERT & GARDINER,
OF BROOKLYN, NEW YORK, A FIRM.

HIGH HEEL FOR SHOES.

1,293,992.

Specification of Letters Patent.

Patented Feb. 11, 1919.

Application filed April 27, 1917. Serial No. 164,843.

To all whom it may concern:

Be it known that I, JOHN L. VAN NESS, a citizen of the United States, and residing in the borough of Brooklyn, county of Kings, 5 city and State of New York, have invented certain new and useful Improvements in High Heels for Shoes, of which the following is a full and complete specification.

My invention relates to an improvement 10 in high heels for shoes, and has for its object to devise a method of making such heels in a novel and advantageous manner.

In supplying high heels for the shoes of women, the custom heretofore has been to 15 fashion the body of the heel out of layers of leather, nailed or glued together; or out of wood, covered with leather, or celluloid, or cloth, to match with the upper. Such leather and covered wooden heels, however, 20 are quite expensive; and wooden heels necessitate the turning out of the heel through the instrumentality of a lathe, or other machine, in a wood-working shop; and, when the heel has received its shape, the covering 25 of the heel with leather or some other substance, preparatory to its delivery to the shoe manufacturer, who attaches it to the shoe in the required position. This requires very often the shoe manufacturer to wait for 30 the heels.

By my invention a more substantial heel may be produced than a separate covered wooden heel, and can be begun and finished directly in the shoe factory (being part of 35 the shoe) during its manufacture; without requiring wood-working machinery, and will be light, durable and resilient, and therefore constitute a very superior article.

The above-mentioned and other objects 40 and advantages of my improvement are set forth in the following description, together with the accompanying drawings, which illustrate one embodiment of my invention. This disclosure, however, is illustrative only; 45 and embodiments of my inventive idea other than that actually shown herein may of course be resorted to, within the limits indicated by the general terms in which the claims are expressed and by the variations 50 in the phrasing of the same.

On the drawings:—

Figure 1 shows in side elevation a shoe to which is affixed a heel made according to an

embodiment of my invention, in its initial stage, with the parts making up the heel assembled in the rough;

Fig. 2 shows a side view of a shoe having such a heel after the heel has been worked into shape;

Fig. 3 is a side view of a shoe having such a heel in finished form;

Fig. 4 is a vertical, longitudinal, sectional view of the heel shown in Fig. 3, and the adjacent part of the shoe carrying it;

Fig. 5 is a vertical, longitudinal, sectional view of a slightly modified form;

Fig. 6 is a vertical transverse section along the lines 6—6 of Fig. 4; and

Fig. 7 is a plan view of the heel with the top piece removed.

The same characters identify the same parts throughout.

Referring to the drawings, a shoe 1 is provided with a sole 2 extending from the front end to the back; and to the rear end or heel 75 seat 2^a of the sole 2, I attach by nails a number of superposed layers of leather-board. Thereafter, I attach to the first section, a second or third section, depending upon the height, by nails, to make the heel 3. Previous to being attached to the sole of the shoe, the layers or sections are of course given substantially the peripheral shape of the heel in a general contour; and they will be of the approximate size required from top 80 to bottom, as will be understood, and as indicated in Fig. 1.

In Fig. 1 the layers are shown affixed to the heel seat by assembling the same in the rough; the heel seat at the beginning having its side and rear edges extended, as at 2^b; and the layers or sections may be partly of leather and partly of some other cheaper substance such as leather board, or entirely of leather board; which is made out of 95 scraps of leather, and somewhat resembles pasteboard in appearance and properties. I begin by affixing to the heel seat several layers of leather board, indicated by the numeral 4, constituting the first section, and these are secured by driving nails by machine therethrough into the sole and clinching the nails in the same way as in the case of heels comprising layers of leather only. On the leather board layers 4, I next place 100 several layers of leather or leather board 5;

attaching the leather or leather board layers by means of nails in the same way, and to increase the height additional layers 4 and 5 are required. The last layer 5 is given before being applied a configuration which it will retain, when the heel is being finished. The layers adjacent the heel seat are preferably given a concave shape by compression, as at 4^a (Fig. 6), before being attached, so that they better conform to the heel seat.

With the layers secured to the sole or heel seat, the heel is turned down to its proper size, and shaped either in a machine or by hand. In the course of this operation, the edges of the layers 4 and 5 and the adjacent edges of the heel seat of the sole 2 are trimmed off so as to make the sides and back of the heel present a smooth and uniform surface. Of course, the front or breast 10 of the heel is likewise worked in order to obviate the rough edges of the layers 4 and 5 thereat. Fig. 1 presents broken lines extending through the layers 4 and 5 to indicate the extent to which these layers and the heel seat are to be ground off to trim the same; and Fig. 2 indicates how the heel will look when the operation of trimming is finished. This turning down just described is governed by the configuration of the last layer 5, and this turning down is carried out in respect to this last layer 5.

The covering for the heel is then applied and is indicated by the numerals 6 in Figs. 3, 4 and 6. It is preferably of leather or celluloid or cloth, or some other similar substance, and is cemented over the sides and back of the heel to present a smooth surface. At its lower extreme edge this covering is turned over against the exposed face of the last layer 5 and those free edges 11 are cemented thereto, (Fig. 7), and along its upper edge it is forced, by means of a suitable thin-bladed tool, over the heel seat and under the counter seat at 13 so as to become clamped by and between the counter seat of the upper and the heel seat of the sole. For this purpose the upper and lower edges of the covering 6 may be thin or beveled by 45 skiving, as indicated at 7 in Figs. 4 and 6; and the front or breast part of the heel, while it may be left uncovered, is preferably provided with a covering 6 likewise. Either one part of the covering of the heel or the 55 free edges of said covering may be clamped down on the breast of the heel, and the apron of the sole may cover the breast of the heel and these free edges. The covering for the front of the heel will, of course, be cemented to the heel, and the covering for the sides and back of the heel may have the front corners thereof, indicated by the numeral 8 in Fig. 4 adjacent to the sole 2, flattened and pressed against the edge or 65 side of the sole so that the surface of the

covering may merge with the surface of the side of the sole, and avoid projections at these points.

After the cover is secured to the heel, I affix a section or layer or tread piece 15 of leather to the covered heel, placing this leather tread-piece so that it will press against the overturned lower free edges of the cover; and securing the same by nails or screws to prevent detachment. This last-named tread-piece or top lift 15 affords a suitable wearing surface for the heel.

In the form shown in Fig. 5, all of the layers are of leather board.

By means of the heel made in the above manner, the cost of production is greatly decreased, because a great portion of the heel is made up of leather board, which is less expensive than leather. The covering 6, of course, can be cloth as well as leather, or it may even be of some other substance, such as shellac, varnish, celluloid, etc.

As hereinbefore stated, heels made of leather layers only, though requiring no covering, are more expensive; and wooden heels have to be made separate from the shoe, and after being attached thereto, the edge of the sole around the heel seat must be separately trimmed off to suit, that is, to fit the wooden heel. In addition, the heel seat must be trimmed to a convex shape to fit the concave or cup shape of the wooden heel. Furthermore, the wood does not wear well as it is stiff and hard, and has only a small leather-wearing surface. When this leather-wearing surface is worn down, the wood becomes exposed, and will speedily edge up and become soft. Furthermore, a wooden heel will often split, even before the leather-wearing surface is completely worn down.

The sections may be made up separately, or the layers may be added separately, to form the heel.

Furthermore, wooden heels require special machines and skilled labor for the purpose of making such heels. Hence, the shoe manufacturer must either add to the expense of his plant by having his own woodworking shop, or he must have the heels made elsewhere; the latter alternative often entailing delays in delivery. By manufacturing heels according to my invention, no woodworking shop or skilled wood cutters are needed, and all of the operations entailed in the production of heels comprising layers of leather board and leather can be started and carried through in the shoe factory, without additional machinery, and as forming part of the shoe manufacture. The manufacturer can thus always be sure of keeping his manufacture agoing, and never has to wait on outside sources for this part of his stock as he must with wooden heels. A heel made as hereinbefore set forth is not only very much cheaper to produce, but is also light, re-

silient and durable for all conditions of use. The shoe repairer can readily repair the heel, by replacing layers and a new cover, thus readily matching the parts. In wooden 5 heels, this cannot be done, as it takes sometimes a week to match a wooden heel.

It will be appreciated that my invention, by facilitating the manufacture of the heel in the factory where the other parts of the 10 shoe are originated and put together, enables the various operations involved in shoe production to be more closely coördinated; and this fact is quite important to the manufacturer when the separate items making up the 15 expense of operating a plant are taken into consideration.

I have described and illustrated preferred and satisfactory embodiments of my invention, but it is obvious that changes may be 20 made therein, within the spirit and scope thereof, as described in the appended claims.

I claim:

1. A method of making covered heels for 25 shoes, which consists in attaching an uncovered heel to the shoe, applying a cover to said heel, and forcing the upper edge of said cover tightly inward to form a substantially horizontal flange the lower surface of which is in close contact with the upper surface of 30 the heel portion of the sole while the upper surface of said inturned flange is in close contact with the lower surface of the counter-

portion of the upper, whereby said upper edge flange will be clamped in a substantially horizontal position, by and between 35 the sole and the upper.

2. That step in the art which consists in assembling in the rough, directly upon the heel seat of the shoe and successively, a plurality of layers of leather material, then 40 affixing to the last-attached of said layers, a top layer of accurately predetermined shape, trimming the edges of the previously applied layers and of the heel seat in respect to said top layer while leaving the 45 latter unaltered, applying a covering to the edges of all of said layers and to said heel seat and turning the lower edges of said covering over against the exposed face of said top layer, forcing the upper edges of 50 said covering inwardly between the upper counter seat and the heel seat, to be clamped by and between the sole and the upper, and finally securing a top lift to the said top layer against the inwardly turned lower 55 edges of the covering to provide a wearing surface for the heel.

In testimony that I claim the foregoing as my invention, I have signed my name in presence of two subscribing witnesses.

JOHN L. VAN NESS.
